DESIGN FOR TEXTILE FABRIC

Samuel E. Staines, Allendale, N. J.

Application May 4, 1939, Serial No. 84,787

Term of patent 3½ years

To all whom it may concern:

Be it known that I, Samuel E. Staines, a citizen of the United States, residing at Elmwood Avenue, Allendale, in the county of Bergen and State of New Jersey, have invented a new, original, and ornamental Design for Textile Fabric, of which the following is a specification, reference being had to the accompanying drawing, forming part thereof.

The figure of the drawing is a plan view of a piece of textile fabric showing my design.

The design consists of a series of three uniformly spaced narrow stripes of a boucle-like texture separated by a wide stripe of the same texture on a plain background as shown.

I claim:

The ornamental design for textile fabric, as shown and described.

SAMUEL E. STAINES.
